UNITED STATES PATENT OFFICE.

JOSEPH WILLIAM MILLER, OF MIAMI, OKLAHOMA, ASSIGNOR OF ONE-FOURTH TO
WILLIAM P. NEFF, ONE-FOURTH TO FRANKLIN E. SMITH, AND ONE-FOURTH TO
JAMES C. VAUGHAN, ALL OF MIAMI, OKLAHOMA.

ORE-SEPARATING MACHINE.

1,306,270.

Specification of Letters Patent. Patented June 10, 1919.

Application filed December 28, 1918. Serial No. 268,616.

To all whom it may concern:

Be it known that I, JOSEPH WILLIAM MILLER, a citizen of the United States of America, and a resident of Miami, in the county of Ottawa and State of Oklahoma, have invented certain new and useful Improvements in Ore-Separating Machines, of which the following is a specification.

This invention relates to improvements in ore separating machines of that character in which it is possible to use material directly from the rolls without the use of screens, and yet be able to take out all sizes of ore from the finest to the coarsest, thereby eliminating the use of screens, jigs, and sludge tables.

The preferable embodiment of my invention will be hereinafter described and illustrated in the drawings appended hereto, and then definitely claimed at the end hereof.

In the aforesaid drawings which illustrate the preferable, but not necessary, embodiment of my separating machine:

Figure 1 shows a representation of my invention, two separating machines being illustrated on one shaft, and one of them in section in order that the operation may be better understood.

Fig. 2 is an elevation taken at right angles to that shown in Fig. 1.

Fig. 3 is a section through the line 3—3 of Fig. 1.

Fig. 4 is a horizontal section through the line 4—4 of Fig. 1.

Fig. 5 is a horizontal section through the line 5—5 of Fig. 1.

Fig. 6 is a bottom plan view of part of the structure shown in Fig. 4.

Referring now to the details of the drawings by numerals: 1 and 2 designate a framework which may be of any desirable construction but which, in the drawings, is shown as being provided with horizontal members 7, 8, 9 and 10, but it will be understood that these may be varied as occasion may require.

Power is transmitted to the operative parts of the machine by means of a vertical shaft 12 to which a pulley 14 may be applied. When I use two separators on the same shaft, they are arranged as shown in Figs. 1 and 2, and hence there is, for each separator, a receiving hopper 16 to which the material is supplied, and within the

hopper there is a spreading cone 18 (see Fig. 1). The material, after it is spread outward by the cone 18, passes down through the bottom of the hopper, and it will be observed that the opening at the bottom of each hopper is larger than the shaft 12 in order that the material may pass out through the opening onto a cone 20 adjustably secured to the aforesaid shaft 12. This cone 20 is adjustable in order that it may be raised or lowered according to the coarseness or fineness of the ore. The dirt and water after passing through the opening in the bottom of the hoppers 16 pass down over this cone which is, of course, rotating with the shaft 12. Supported underneath the adjustable cone 20 is a non-rotatable device comprising a bottom member 22 forming a central receptacle, and located around the edges of the bottom, at some elevation above the receptacle, are two annular rims 24 and 26, the rim 26 having beyond it a third rim 28 which is slanting, as shown in the drawings, in order to carry off the tailings as will be described. The aforesaid adjustable cone 20 has its edges projecting down inside of the space left by the annular rim 24, and as the material passes down the cone, the water and tailings will pass over the rim 24 while the ore will collect and pass under the cone 20 and finally reach the receptacle formed by the bottom 22. Projecting downwardly from the inside of the cone 20 are four vanes or wings 30, shown also in Figs. 4 and 6. These, rotating with the cone 20, are for the purpose of propelling the ore toward the center and compelling it to pass up over an upwardly projecting rim 32 so that the ore will pass over the rim 32 and into the ore flume 34 from which it may be passed out to any desired collecting device. The water and the tailings, together with any ore which may not have collected on the inside of the rim 24 of the upper separator, will pass over, as illustrated in Fig. 1, and be finally collected by the rim 28 and passed out through a chute 36 of the upper separator into the hopper 18 of the lower separator. In the lower receptacle the tailings would pass into a chute 40 from which they may be sent to any desired point.

In operation, the material is delivered to the first of the hoppers 16 and after passing

under the spreading cone therein passes out through the bottom of the hopper and onto the large rotatable cone 20, and proceeds down the cone as the latter rotates. As the 5 material passes down the cone it begins to separate and by the time it reaches the lower edge of the cone the ore is separated from the tailings, the ore passing inside of the rim 24 while the tailings pass over said rim 10 and finally through the tailings outlet, while the ore, caught by the rim 24, will pass under the adjustable cone and be propelled inward and upward by means of the rotatable vanes or wings 30 until the ore 15 is compelled to pass through the flume 34. If the separation in one machine is not sufficiently fine, the outlet directs the tailings into the hopper of a second separator where the same operation will be repeated only 20 with greater fineness.

From the foregoing and accompanying drawings, it will be seen that I have invented a very simple ore separator by which I am enabled to dispense with any screens, jigs or 25 sludge tables and yet have produced a separator so simple and compact that ordinary attendants can take care of the same, even to the extent of adjusting and repairing it.

It will be obvious that changes may be 30 made in the form and construction of my invention without departing from the spirit thereof and that the drawings show the preferable, but not necessary, embodiment, so that reference should be made to the accompanying claims in order to determine the 35 scope of the invention.

What I claim as my invention is:

1. In a device of the character described, the combination of a rotatable cone adapted 40 to receive the material to be treated and permit it to gravitate therefrom, and collecting devices comprising receptacles divided by a circumferential rim or ledge, the latter extending upwardly and just outside of the 45 bottom edge of the said cone, whereby the heavy material passes downward by gravity and slides off of said cone inside of said rim or ledge and into the inside receptacle and the tailings pass over said rim or ledge into 50 the receptacle outside of said cone.

2. In a device of the character described, the combination of a receptacle for receiving the material to be treated, a cone receiving the material from said receptacle, and permitting it to pass downward over the surface 55 of the cone, as the said cone revolves, whereby the ore is separated from the tailings, and a receptacle located under said cone and having a rim extending upwardly and just 60 outside of the lower edge of the cone, the tailings passing over the said rim and the ore passing down between the rim and the edge of the cone, as the latter rotates into the receptacle under said cone.

3. In a device of the character described,

the combination of a receptacle for receiving the material to be treated, a cone receiving the material from said receptacle, and permitting it to pass downward over the surface of the cone, as the said cone revolves, 70 whereby the ore is separated from the tailings, a receptacle located under said cone and having a rim near the lower edge of the cone, the tailings passing over the said rim and the ore passing down between the rim 75 and the edge of the cone, as the latter rotates, a discharge for the ore, and rotatable wings propelling the ore inward from the edge of said cone to said discharge.

4. In a device of the character described, 80 the combination of a rotatable cone adapted to receive the material thereon and permit it to pass downward over the surface of the said cone, as said cone revolves, whereby the ore is separated from the tailings, a receptacle under said cone having a rim extending 85 upwardly and just outside of the lower edge thereof, and a discharge for the tailings, the latter passing over the said rim into said discharge, and the ore passing down between 90 the rim and the edge of the cone, as the latter rotates into the receptacle under said cone.

5. In a device of the character described, the combination of a rotatable cone adapted 95 to receive the material thereon and permit it to pass downward over the surface of the said cone, as said cone revolves, whereby the ore is separated from the tailings, a receptacle under said cone having a rim near the 100 lower edge thereof, a discharge for the tailings, the latter passing over the said rim into said discharge, and the ore passing down between the rim and the edge of the cone, as the latter rotates, a discharge for the 105 ore, and rotatable wings propelling the ore inward from the edge of said cone to said discharge.

6. In a device of the character described, the combination of a rotatable cone adapted 110 to receive the material to be treated and permit it to gravitate therefrom, collecting devices comprising receptacles divided by a circumferential rim or ledge, the latter extending upwardly and just outside of the 115 bottom edge of the said cone, whereby the heavy material passes downward by gravity and slides off of said cone inside of said rim or ledge and into the inside receptacle and the tailings pass over said rim or ledge into 120 the receptacle outside of said cone, and an annular discharge chamber outside of the last named receptacle receiving the tailings therefrom and having a slanting bottom to discharge the tailings.

7. In a device of the character described, the combination of a rotatable cone adapted to receive the material thereon and permit it to pass downward over the surface of the said cone, as said cone revolves, whereby the 130

ore is separated from the tailings, a receptacle located under said cone and having a rim near the lower edge of the cone, a slanting annular discharge chamber to receive the 5 tailings floating over the aforesaid rim, the ore passing down between the rim and the edge of the cone as the latter rotates, a central discharge for the ore, and wings rotatable with the aforesaid cone adapted to pro-

pel the ore inward from the edge of the cone 10 to said central discharge.

In testimony whereof I affix my signature in presence of two witnesses.

JOSEPH WILLIAM MILLER.
